(57) **CLAIM**

The ornamental design for a wafer level focus lens assembly, as shown and described.

DESCRIPTION

FIG. 1 is a perspective view of a wafer level focus lens assembly;

FIG. 2 is a top elevation view thereof;

FIG. 3 is a bottom elevation view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines in the drawings depict portions of the wafer level focus lens assembly that form no part of the claimed design.
